Application April 21, 1936, Serial No. 75,578

19 Claims. (Cl. 292—336)

This invention has to do generally with latch mechanisms, and particularly of the type mounted on the outside of cabinets and the like. By reason of certain features and characteristics later described, the present latch is especially suitable for use on refrigerator cabinets wherein an air tight seal is provided around the door by keeping the latter pressed tightly against a resilient and compressible gasket or door frame lining.

One of my principal objects is to provide a spring latch having self closing characteristics enabling the latch not only to hold the door closed, but to apply and constantly maintain on the door, sufficient pressure or power to tightly compress a gasket against which the door may close, thereby assuring an air tight seal. In this respect, the present latch is particularly advantageous and effective in that it is not dependent in its closing action upon the door first being manually swung to fully closed position, that is to a final position in which the gasket is fully compressed. Instead, the latch itself acts to crowd the door against and to fully compress the gasket, without pressure having to be applied manually. Another feature of the invention is the elimination of any possibility of the parts of the latch becoming broken or damaged as a result of the latching member being slammed or otherwise forcibly closed against the keeper. As is commonly known, this is a fault inherent in many spring latches of this general type. The invention overcomes any such difficulties by providing a latch mechanism which acts automatically upon opening movement and subsequent release of the handle as the door is opened, to retain the latching member in partially open or retracted position, instead of in closed or projected position, so that the resistance which it encounters upon engagement with the keeper as the door is swung shut, will be insufficient to cause any injury to the latch.

The invention serves various additional objects, and embodies numerous other features contributing to the provision of a highly satisfactory and efficient latch. All these however will be most readily understood and explained to best advantage in the following detailed description of the invention in one of its typical and preferred forms. Reference is had throughout the description to the accompanying drawings, in which:

Fig. 1 is an elevation showing the latch applied to a refrigerator cabinet;

Fig. 2 is a section on line 2—2 of Fig. 1;

Fig. 3 is a plan view of the latch mechanism placed horizontally;

Fig. 4 is a view looking into the bottom of the latch in the aspect of Fig. 3;

Fig. 5 is a section on line 5—5 of Figs. 3 and 4 showing the latch parts in their normal closed positions;

Fig. 6 is a view similar to Fig. 5 showing the positions of the parts with the handle in full open position;

Figs. 7 and 8 are views showing the relative positions of the crank arm and keeper corresponding to Figs. 5 and 6, respectively;

Fig. 9 shows the position of the locking element with the crank being held partially open;

Fig. 10 illustrates the position of the locking element at the point of crank release;

Fig. 10a is a fragmentary section on line 10a—10a of Fig. 10;

Fig. 11 is a section on line 11—11 of Fig. 5;

Fig. 12 is a plan view, partly in section, as indicated by line 12—12 of Fig. 13, showing a variational form of the invention;

Fig. 13 is a longitudinal section on line 13—13 of Fig. 12, the cap portion of the body being removed in this view; and

Figs. 14 and 15 are fragmentary views illustrating different positions of the latch mechanism.

In Fig. 1, I have shown the latch mechanism, generally indicated at 10, applied to the cabinet C of a refrigerator or the like, the keeper 11 being attached to the cabinet frame 12 by screws 13, and the crank operating part 14 of the latch being secured to the door 16 by screws 15. As previously mentioned, the present latch is particularly suitable for cabinets in which the door closes against a gasket or other sealing means that is compressed as the door is brought to fully closed position. According to the customary practice of using a gasket to provide an air-tight seal around a refrigerator cabinet door, as illustrated in Fig. 2, the door frame 12 is lined with a tubular rubber gasket 17 against which the outer shoulder 16a of the door closes. It will be understood that by reason of the compressibility of the gasket, the latter offers a yielding resistance to closing of the door, and that the tighter the door is pressed against the gasket the more effectively will the gasket seal around the door.

As best illustrated in Figs. 7 to 9, the keeper 11 comprises a base 18 fastened to the door frame, 50 and a hook-shaped portion 19 having a crank arm receiving opening 20 at one side of the web 21. Portion 19 is shaped to provide a beveled surface 22 and an interior beveled or angular shoulder 23, the outer portion 23a of which slopes 55

with relatively great angularity or curvature toward the base 18, and the inner portion 23b having a slope in that direction of somewhat less angularity. The crank engages and moves along 5 the angular keeper shoulder 23, and is influenced by the particular shape of the shoulder to accomplish a progressive tightening of the door closure against the gasket 17, all in the manner hereinafter described.

10 The crank arm operating mechanism is contained within a hollow body 25 having flanged ends 25a and a cover piece 26 secured to the other portion 25 of the body by screws 27, as best illustrated in Figs. 4 and 5. The body contains an 15 oscillatory part 28, which I term generally the latching member, comprising a shaft 29 journaled in bearings 30 formed in the body between portions 25 and 26, and an integral crank-shaped arm 31 having at its outer end a wrist pin 32 20 carrying a roller 33 which is received within the keeper 11. In certain of its broad aspects, the invention is not necessarily limited to the use of a latching member of any particular shape, although I prefer, for various reasons that will be 25 apparent from the following description, to make it in the form of an oscillatory crank. Normally the crank arm is yieldably pressed in a direction tending to move the roller 33 into the keeper, see Figs. 5 and 7, by a pair of strong coil springs 34 30 attached at 35 to the body and at 36 to the hooked extremities 37, see Fig. 11, of a bifurcated projection 38 on the shaft 29. It may be mentioned at this point that springs 34 not only act to swing the crank arm into the keeper, but, by virtue of 35 their strength, also to exert through the crank a strong closing force on the door acting to press it tightly against the gasket 17.

The crank arm is rotated to withdraw it from the keeper by means of a handle 40 extending 40 through a slot 41 in the cover portion 26 of the body. The shaft 29 extends through an opening in the inner end 40a of the handle, see Fig. 11, so that the handle is pivotally mounted on the shaft and capable of rotation relative thereto. 45 Swinging the handle from the position of Fig. 5 to that of Fig. 6, causes the crank arm 31 to be swung sufficiently to bring roller 33 clear of the keeper, by the engagement of shoulder 42 on the handle with an angular shoulder 43 on lug 44 50 projecting from the shaft 29. A force is constantly applied to the handle 40, tending to return it to what may be termed the closed position of Figs. 5 and 9, by a coil spring 45 fastened at 46 to the handle, and at 47, see Fig. 4, to a 55 tongue-shaped portion 48 of the body which, as will presently appear, serves as a stop for the locking element.

For the purpose of holding the crank arm in partially open position I provide a locking device, indicated at 49, which may be generally described as serving to lock the latching member 28 against closing movement under the influence of springs 34, once the crank has been swung to at least partially open position, and which operates to release the crank into the keeper, as a result of the crank being brought into engagement with the keeper as the door is closed. In its preferred form, the locking device comprises a detent bar 49a pivotally supported at one end 60 on pin 58, and having near its opposite end an opening 51 which receives a lug 52 projecting from shaft 29 at a point between the spring attachment arms 37, see Fig. 11. When the latch is closed, with the parts in the positions shown in 70 Fig. 5, locking bar 49a is held out of engagement

with the shaft lug 52 and against stop 48, by a spring 53 fastened at 54 to the body and bearing at its other end 53a against the locking bar at the inside of pin 50.

As the handle 40 is swung toward open position, however, locking bar 49a is brought into engagement with lug 52 by means of a yielding connection between the bar and handle which becomes effective to swing the bar against the resistance of spring 53 only after the handle has 10 been swung some distance in an opening direction. This yielding connection between the handle and lock bar consists of coil spring 55 fastened at 56 to the handle and having an opposite looped end 56a passing through the bar 49a. The looped end 56a of the spring provides, in effect, a lost motion connection with the lock bar, the loop being sufficiently long that not until handle 40 has been swung say 5° or 10° from the closed position of Fig. 5, will the end of the loop 56a engage bar 49a to pull it down against lug 52. Thus, such lost motion connection between spring 55 and the locking bar enables spring 53 to keep the latter disengaged from lug 52 when the handle is closed, without having to maintain a nicety 25 of balance between the forces exerted by springs 55 and 53, that would be required in the absence of some such allowance for lost motion in the connection of spring 55.

The operation of the latch may best be explained by first starting with the parts in the closed position of Fig. 5 in which, as seen by reference to Fig. 7, the crank roller 33 is thrust into the keeper to hold the door 16 pressed against gasket 17. The latch is opened and the crank arm 31 swung to the position of Fig. 8 in which roller 33 clears the rounded nose 19a of the keeper, by swinging handle 40 to the position of Fig. 6, the crank being rotated as a result of the engagement of the handle shoulder 42 with shaft 40 lug 44, as previously explained. While the handle is being swung open, latch bar 49a is pulled into engagement with shaft lug 52 by spring 55 being brought into action to overcome the thrust of spring 53. When the face S of lug 52, swinging in the direction of the arrow in Fig. 6, reaches the end of slot 51 in the locking bar, the latter snaps down to the position of Fig. 6, locking lug 52 within opening 51. In order to bring roller 33 clear of the keeper, it is necessary to swing 50 the handle 40 to such an extent as to rotate lug 52 somewhat beyond the point at which surface S just clears the end of the lock bar opening 51, as will be seen from Fig. 6.

It will be understood that the crank is swung 55 open by handle 40 against the resistance of springs 34, which tend to swing the crank in a closing direction. Upon releasing the handle in the position of Fig. 6, the crank is swung in the direction of the arrow in Fig. 9 to bring lug 52 60 into engagement with the end of opening 51, and is locked against further closing movement until the lock bar is released. The handle, however, is returned to fully closed position by the pull exerted by spring 45. Fig. 9 shows the relative positions of the roller 33 and keeper when the door is being swung closed with the crank held by the locking bar. As the door is swung closed, roller 33 is brought into engagement with the beveled keeper surface 22 near the rounded 70 nose 19a, thus requiring the exertion of some force, though relatively small, on the door to cause the crank arm to be cammed outwardly to the position of Fig. 10, and roller 33 to ride over the nose of the keeper. During this movement, 75

the crank is swung in the direction of the arrow in Fig. 10 to back lug 52 out of the latch bar opening 51, whereupon spring 53 presses the lock bar up against stop 48 to free it from the shaft lug. Springs 34 thereupon exert a strong closing force on the crank, tending to swing it toward the position of Fig. 7 with roller 33 riding along surfaces 23a and 23b.

These are two cooperating factors each serving as a "take-up" means for crowding the door toward a completely closed position and compressing the resilient rubber gasket 17 against which the door is closed. In the first place, when roller 23 contacts the beveled or curved face 23a of the keeper, and as the roller is pulled into the keeper by springs 34, the surface 23 acts as a cam which quickly crowds the door against the resilient rubber gasket 17. Since initial compression of the gasket requires less force than final compression, the initial power can be applied more suddenly and to a greater degree than is necessary to finally complete the compression of the gasket. Thus the keeper surface 23a is given somewhat greater angularity to cause the crank to quickly compress the gasket during the first interval of its travel into the keeper. Then, by reason of the lesser angularity of surface 23b and its correspondingly greater wedging action, the power of springs 34 is applied with greater advantage during the last portion of the crank travel into the keeper, to obtain the greatest pressure against the gasket and thus complete its final compression.

The second "take-up" effect results from the swing of the crank arm from one side to the other of the extreme outer point of contact between the roller and the keeper. Thus in Fig. 8, wherein the center of the shaft 29 is shown to be positioned substantially in line with the outer surface of the keeper nose 19a, arm 31 will be seen to have swung to the right of the center line L-L when in full open position. In closing to the position of Fig. 7, however, the crank swings to the opposite side of the center line, and in so doing, crowds roller 33 against surface 23 to pull the door more tightly against the gasket.

As mentioned, relatively little closing force applied to the door is necessary to cam roller 33 outwardly from the position of Fig. 9 to that of Fig. 10, due to the amount of initial offset of roller 33 relative to the nose of the keeper, and the angularity of beveled surface 22. However, regardless of the closing force applied to the door, and regardless of how hard it may be slammed shut, by no possibility can the crank or other parts of the latch be damaged because, in closing, the crank always will readily be deflected outward to pass the extremity of the keeper.

In Figs. 12 to 15 I show a variational embodiment of the invention that is generally similar to the previously described form, but improved in certain respects, particularly as it is somewhat more compact, certain castings are more easily manufactured, and the working parts are placed in such position that the latch is more readily assembled. The general shape and construction of the body 60, cover piece 61, keeper 62, as well as the latch operating handle 63, the crank arm latching member 64, and its mounting within the body, all are similar to the corresponding parts in the first described form of the invention. Aside from other relatively minor differences, the main distinction is in the construction and

mounting of the lock bar 72 which cooperates with the locking member lug 66.

Coil springs 67 connected at 68 to the latching member and acting to thrust the crank arm roller 69 into the keeper, are attached to pin 70 extending through body lugs 71. On this pin, between the lugs, is pivotally mounted the lock bar 72 extending longitudinally within the body, the bar being notched at 73, see Fig. 12, to provide a shoulder 74 adapted to engage lug 66. When the parts are in the position of Figs. 12 and 13, bar 72 is swung out of locking engagement with the latching member lug 66, by the action of spring 75 attached to lug 76 and to a post or lug 77 integral with the cover piece 61. The opposite end of bar 72 is yieldably connected with the handle 63 by way of coil spring 78, the looped end 78a of the spring extending around the end portion 72a of the lock bar. As illustrated in Fig. 13, when the handle 63 is in closed position, bar 72 is held clear of lug 66 by spring 75, in which position the bar engages the end of the looped portion 78a of spring 78. Spring 79, connecting handle 63 with the body at 80, serves to return the handle to normal position after the latch is operated.

To release the latching member from the keeper, assuming the parts to be in the closed position of Figs. 12 and 13, handle 63 is swung to withdraw the crank arm roller 69 from the keeper and to clear lug 66 of engagement with shoulder 74 of the lock bar, as illustrated in Fig. 14. As the handle is swung, spring 78 overcomes the resistance of spring 75, swinging the lock bar toward lug 66 so as to position shoulder 74 for engagement by the lug after the handle is released, and to lock the crank arm in the partially open position of Fig. 15. From the previously given explanation of the operation of the first described form of the invention, it will be clear how closing movement of the door causes the crank arm and roller 69 to be cammed outwardly from the position of Fig. 15 by engagement with the keeper 62, and lug 66 disengaged from the lock bar and the latter swung by spring 75 to the position of Fig. 13, permitting the latching member to be thrust into the keeper by the action of coil springs 67.

I claim:

1. In a latch mechanism adapted to cooperate with a keeper, the combination comprising, a latching member rotatable about an axis and held against substantial movement longitudinally thereof, said member being adapted to be releasably retained by the keeper, a handle for moving said member to an open position of disengagement from said keeper, means independent of said handle for holding said member in partially open position, and means for releasing said holding means by the engagement of said member with the keeper to permit the member to close into the keeper.

2. In a latch mechanism adapted to cooperate with a keeper, the combination comprising, an oscillatory crank-shaped arm rotatable about an axis and held against substantial movement longitudinally thereof, said arm being adapted to be releasably retained by the keeper, a handle for swinging said arm to an open position of disengagement from said keeper, means independent of said handle for holding said arm in partially open position, and means for releasing said holding means by the engagement of said

- arm with the keeper to permit the arm to close into the keeper.
3. In a latch mechanism adapted to cooperate with a keeper, the combination comprising, a latching member rotatable about an axis and held against substantial movement longitudinally thereof, said member being adapted to be releasably retained by the keeper, a handle for moving said member to an open position of disengagement from said keeper, means independent of said handle for holding said member in partially open position, means for releasing said holding means by the engagement of said member with the keeper to permit the member to close into the keeper, and yielding means thrusting said member into said keeper.
4. In a latch mechanism adapted to cooperate with a keeper, the combination comprising, a latching member rotatable about an axis and held against substantial movement longitudinally thereof, said member being adapted to be releasably retained by the keeper, said keeper having a base and a surface extending angularly toward said base and along which said member moves in closing, a handle for moving said member to an open position of disengagement from said keeper, means independent of said handle for holding said member in partially open position, means for releasing said holding means by the engagement of said member with the keeper to permit the member to close into the keeper, and yielding means thrusting said member into said keeper.
5. In a latch mechanism adapted to cooperate with a keeper, the combination comprising, a latching member adapted to be releasably retained by the keeper, a handle for moving said member to an open position of disengagement from said keeper, a locking element operating independently of said handle to hold said member in partially open position, yielding means for pressing said element into locking engagement with the member when said handle is moved toward open position, and means for releasing said holding means by the engagement of said member with the keeper to permit the member to close into the keeper.
6. In a latch mechanism adapted to cooperate with a keeper, the combination comprising, a member adapted to be releasably retained by the keeper, a handle for moving said member to open position of disengagement from said keeper, a locking element operating independently of said handle to hold said member in partially open position, yielding means for pressing said element into locking engagement with the member when said handle is moved toward open position, means holding said element out of locking engagement with the member when the handle is in closed position, and means for releasing said holding means by the engagement of said member with the keeper to permit the member to close into the keeper.
7. In a latch mechanism adapted to cooperate with a keeper, the combination comprising, a latching member including an oscillatory crank-shaped arm adapted to be releasably retained by the keeper, a handle for swinging said arm to an open position of disengagement from said keeper, means independent of said handle for holding said arm in partially open position, a pair of bearings journaling said member and within which said member is confined against substantial movement axially of the bearings, yielding means acting to thrust said arm into the keeper, and means for releasing said holding means by the engagement of said arm with the keeper to permit the arm to close into the keeper.
8. In a latch mechanism adapted to cooperate with a keeper, the combination comprising, a body, a latching member including a shaft journaled in said body and an oscillatory crank-shaped arm, integral with said shaft, adapted to be releasably retained by the keeper, a handle pivotally mounted on said shaft for moving said arm to an open position of disengagement from said keeper, and a projection on said shaft engageable by the handle to swing said arm to open position.
9. In a latch mechanism adapted to cooperate with a keeper, the combination comprising, a body, a latching member including a shaft journaled in said body and an oscillatory crank-shaped arm adapted to be releasably retained by the keeper, a handle pivotally mounted on said shaft for moving said arm to an open position of disengagement from said keeper, yielding means acting to rotate said shaft and thrust said arm into the keeper, and yielding means, independent of the last mentioned means, resisting movement of said handle to crank arm opening position.
10. In a latch mechanism adapted to cooperate with a keeper, the combination comprising, a body, a latching member including a shaft journaled in said body and an oscillatory crank-shaped arm adapted to be releasably retained by the keeper, a handle pivotally mounted on said shaft and operable to rotate the shaft to move said arm to an open position of disengagement from said keeper, and yielding means acting to rotate said shaft and thrust said arm into the keeper.
11. In a latch mechanism adapted to cooperate with a keeper, the combination comprising, a body, a latching member including a shaft journaled and held against substantial axial movement in said body and an oscillatory crank-shaped arm adapted to be releasably retained by the keeper, a handle for moving said arm to an open position of disengagement from said keeper, yielding means acting to thrust said arm into the keeper, and locking means for holding said arm in partially open position, said locking means being releasable by engagement of said arm with the keeper to permit the arm to close into the keeper.
12. In a latch mechanism adapted to cooperate with a keeper, the combination comprising, a body, a latching member including a shaft journaled in said body and an oscillatory crank-shaped arm adapted to be releasably retained by the keeper, a handle for moving said arm to an open position of disengagement from said keeper, yielding means acting to thrust said arm into the keeper, and locking means for holding said arm in partially open position, said locking means comprising a locking element pivotally mounted within the body and releasably engaging said projection on said shaft.
13. In a latch mechanism adapted to cooperate with a keeper, the combination comprising, a body, a latching member including a shaft journaled in said body and an oscillatory crank-shaped arm adapted to be releasably retained by the keeper, a handle for moving said arm to an open position of disengagement from said keeper, yielding means acting to thrust said arm into the keeper, locking means for holding said

arm in partially open position, said locking means comprising a locking element pivotally mounted within the body and releasably engaging a projection on said shaft, and yielding means urging the locking element into engagement with said projection when said handle is moved to swing the arm to open position.

14. In a latch mechanism adapted to cooperate with a keeper, the combination comprising, a body, a latching member including a shaft journaled in said body and an oscillatory crank-shaped arm adapted to be releasably retained by the keeper, said shaft being rotatable by engagement of said arm with the keeper, a handle for moving said arm to an open position of disengagement from said keeper, yielding means acting to thrust said arm into the keeper, a locking element adapted to releasably engage a projection on said shaft to hold the arm in partially open position, said element being releasable by engagement of said arm with the keeper to permit the arm to close into the keeper, yielding means urging the locking element into engagement with said projection when said handle is moved to swing the arm to open position, and yielding means acting to move said element out of locking engagement with said projection when said shaft is turned by the engagement of said arm with the keeper.

15. In a latch adapted to cooperate with a keeper having a hook-shaped part, the combination comprising a housing, an oscillatory latching member including a shaft journaled in bearings within said housing, a crank arm mounted on one end of said shaft and having a wrist pin carrying a roller adapted to be received within the hook-shaped part of the keeper, a handle mounted on said shaft and operable to swing the crank arm to disengage said roller from the keeper, yielding means connected to said shaft within the housing and urging said arm in a closing direction, a locking element operating to hold said crank arm in partially open position, and yielding means for actuating said locking element.

16. In a latch mechanism adapted to cooperate with a hook-shaped keeper, the combination comprising a housing, an oscillatory latching member adapted to close into said keeper and including a shaft journaled within said housing, and a crank arm mounted on one end of the shaft and having a wrist pin carrying a roller; a projection on said shaft, a crank arm actuating spring attached to said projection, and means for holding said crank arm in partially open position, said means comprising a pivotally mounted bar, means on said shaft engageable

with said bar, and yielding means for actuating the bar.

17. In a latch mechanism adapted to cooperate with a hook-shaped keeper having an outer beveled face, the combination comprising a housing, an oscillatory latching member including a shaft journaled in bearings within said housing, a crank arm mounted on one end of said shaft and having a wrist pin carrying a roller, a projection on said shaft, a spring connected to said projection and urging said crank arm toward closed position, means for holding said arm in partially open position, said means comprising a pivotally mounted bar and a member carried on said shaft engageable with said bar, yielding means for actuating said bar, said roller being adapted to engage the beveled face of the keeper and acting to swing said crank arm to open position and thereby release said bar from holding engagement with said second member.

18. In a latch mechanism adapted to cooperate with a keeper having a base and a surface extending angularly toward said base, the combination comprising, a latching member including an oscillatory crank-shaped arm adapted to be releasably retained by the keeper and to move along said surface in closing into the keeper, a handle for swinging said arm to an open position of disengagement from said keeper, means independent of said handle for holding said arm in partially open position, a pair of bearings journaling said member and within which said member is confined against substantial movement axially of the bearings, yielding means acting to thrust said arm into the keeper along said keeper surface, means for releasing said holding means by the engagement of said arm with the keeper to permit the arm to close into the keeper.

19. In a latch mechanism adapted to cooperate with a keeper having a base and a crank arm engaging surface extending inwardly from the mouth of the keeper opening toward said base at a relatively great angle and then at a lesser angle, the combination comprising, a body, a latching member including a shaft journaled in said body and an oscillatory crank-shaped arm adapted to be releasably retained by the keeper, a handle pivotally mounted on said shaft and extending through an opening in the body and cooperating with said shaft to rotate the shaft and swing the crank arm to an open position of disengagement from said keeper, and yielding means acting to thrust said arm into the keeper.

ELIHU C. WILSON.
